UNITED STATES PATENT OFFICE.

DAVID DENYVEN, OF CAMBRIDGEPORT, MASSACHUSETTS.

DESIGN FOR FURNITURE.

Specification forming part of Design No. 6,237, dated November 5, 1872.

To all whom it may concern:

Be it known that I, DAVID DENYVEN, of Cambridgeport, in the county of Middlesex and State of Massachusetts, have invented and produced a new Design for Furniture, of which the following is a full, clear, and exact description, reference being had to the accompanying photograph forming part of this specification.

In the photograph each piece of furniture is provided at the center of the upper portion of its back with a raised panel rosette, A, beneath which is a raised panel, b. In the face of each back post B is a flute or sunk molding, c, over which is a Grecian scale, d. Upon the surface of the front of each of the arms C and at the top thereof is a head or medallion, e, beneath which is a plain veneered panel, f.

Furniture made in accordance with the above-described design is exceedingly ornamental, and presents a beautiful and unique appearance.

Claim.

What I claim as my invention, and desire to secure by Letters Patent, is—
The design for furniture, substantially as herein shown and described.

Witness my hand this 22d day of August,
A. D. 1872.

DAVID DENYVEN.
